UNITED STATES PATENT OFFICE.

KARL WIMMER, OF SECKENHEIM, NEAR MANNHEIM, AND KARL HART AND ANTON HERTEL,
OF MANNHEIM, GERMANY.

APPARATUS FOR PRESSING CIGARS.

No. 923,281.

Specification of Letters Patent.

Patented June 1, 1909.

Application filed October 17, 1908. Serial No. 458,312.

To all whom it may concern:

Be it known that we, KARL WIMMER, cigar-assorting master, residing at Seckenheim, near Mannheim, Germany, KARL 5 HART, mechanician, residing at 31 Eichelsheimerstrasse, Mannheim, Germany, and ANTON HERTEL, merchant, residing at 49 Meerfeldstrasse, Mannheim, Germany, have invented a certain new and useful Apparatus

10 for Pressing Cigars, of which the following is a specification.

The object of our invention is an apparatus, by means of which cigars of every kind and size in packets of 1/20 thousand or 15 50 pieces may be readily, uniformly and thoroughly pressed from both sides as well as from above as required.

The invention consists in the novel construction, combination and arrangement of 20 parts hereinafter more fully described, illustrated, and claimed.

In the accompanying drawings, Figure 1 is the front-elevation of an apparatus constructed in accordance with this invention; 25 Fig. 2 is the plan view of the same from above; Fig. 3 is the plan view from below, and Fig. 4 is a side-elevation.

The apparatus consists of a wooden box with a rigid bottom *a*, a rigid back-wall *b*, 30 two movable side-walls *c*, and a movable cover, but without a front wall. The cover consists of three separate wooden blocks *d*¹, *d*² and *d*³, and two pieces *d*⁴ and *d*⁵ of sheet-metal overlapping each other and fixed to 35 the two outer blocks *d*¹ and *d*³; *d*⁶ is a bar fixed in the block *d*¹ and projecting through a bore of the block *d*² and into a bore of the block *d*³.

*e*¹, *e*² are two cramp-irons, the vertical 40 arms *e*¹ of which are fixed to the side-walls *c*, while their horizontal arms *e*² project into a groove *a*¹ of the bottom *a* and lie close to the under face of the same. At the end of the horizontal arm *e*² of each cramp-iron there is 45 fixed a screw-nut *f*, through which projects a right- and left-hand threaded screw-spindle *g* lying in the groove *a*¹. This screw-spindle is rotatably mounted in a bearing *h* fixed to the bottom *a* and carries on its one end a 50 hand-wheel *i*.

k are two rotatable and vertically movable 55 holders for the cover *d*, made of wire, the straight shaft of which projects into a somewhat larger bore *l* of the side-wall *c*, while their annular head rests upon the block *d*¹ or

*d*³ of the cover. In each bore *l* there is located a helical spring *m* surrounding the shaft of the holder *k*, the lower end of which rests upon a disk *n* carried by the holder *k*, while its upper end abuts on a plate *o* fixed to the upper edge of the side-wall *c*. 60

The upper edge of the back-wall *b* is provided with a scale *p* for measuring the movement of the side-walls *c*.

The cigars to be pressed being loosely inserted into the pressing-box, the cover *d* being put upon the cigars, and the holders *k* being turned over the blocks *d*¹ and *d*³, the screw-spindle *g* is turned by means of the hand-wheel *i*, whereby the nuts *f*, and with 70 these the cramp-irons *e*¹, *e*², and the side-walls *c* are forced toward each-other to a certain extent indicated by the scale *p*, so that the cigars receive the required horizontal pressure from both sides. In order to give 75 them also the required vertical pressure from above, the pressing-box with the cigars contained therein is then put into an ordinary hand-press, in which the cover *d* is pressed down on the cigars. In the horizontal pressing operation the blocks *d*¹, *d*³ and *d*⁵ as well as the sheet-metal pieces *d*⁴ and *d*⁵ of the cover are also forced toward each other by the side-walls *c* and at the same time raised by the expanding cigars against the action of the elastic holders *k*, but without allowing 80 the cigars to slide over one another. 85

What we claim as our invention and desire to secure by Letters Patent is:—

1. An apparatus for pressing cigars comprising in combination, a box provided with a rigid bottom, a rigid back-wall, movable side-walls, and a movable cover of variable length, elastic holders for said cover, and means for forcing said side-walls toward each other. 90

2. An apparatus for pressing cigars comprising in combination, a box provided with a rigid bottom, a rigid back-wall, movable side-walls, and a movable cover consisting of two or more separate blocks, two sheet-metal pieces overlapping each other and fixed to the outer blocks, and a bar fixed in one of said blocks and projecting into a bore of the others, elastic holders for said cover, and means for forcing said side-walls, said blocks and said sheet-metal pieces toward each other. 100

3. An apparatus for pressing cigars comprising in combination, a box provided with 105

110

a rigid bottom, a rigid back-wall, movable side-walls having bores, and a movable cover of variable length, holders for said cover made of wire, a vertical straight shaft for each holder, said shaft projecting into the bore of the respective side-wall, horizontal annular heads provided on the vertical shafts, said heads resting upon said cover, springs located in said bores, surrounding the shaft of said holders and pressing them downward, and means for forcing said side-walls toward each other.

4. An apparatus for pressing cigars comprising in combination, a box provided with a rigid bottom having a groove, a rigid back-wall, movable side-walls, and a movable cover of variable length, elastic holders for said cover, cramp irons fixed to said side-walls, projecting into the said groove and lying close to the bottom, screw-nuts fixed to said cramp-irons, and a right- and left-hand threaded screw-spindle mounted in a bearing fixed to said bottom, projecting through said screw-nuts and carrying a hand-wheel.

5. An apparatus for pressing cigars comprising in combination, a box provided with a rigid bottom, a rigid back-wall, movable side-walls, and a movable cover consisting of two or more separate blocks having bores, two sheet-metal pieces overlapping each other and fixed to the outer blocks, and a bar fixed in one of said blocks and projecting into the bore of the others, elastic holders for said cover, cramp-irons, fixed to said side-walls, screw-nuts carried by said cramp-irons, and a right- and left-hand threaded screw-spindle mounted in a bearing fixed to said bottom and projecting through said screw-nuts.

In testimony whereof we have hereunto signed our names to this specification in presence of two subscribing witnesses.

KARL WIMMER.
